Primary Examiner — Selina Sikder(74) *Attorney, Agent, or Firm* — Guy J. Houle; HOULE PATENT AGENCY(57) **CLAIM**

The ornamental design of a control for heated wearables, as shown and described.

DESCRIPTION

FIG. 1 is a perspective view of the control for heated wearables;

FIG. 2 is a front view thereof;

FIG. 3 is a right side view thereof;

FIG. 4 is a left side view thereof;

FIG. 5 is a top end view thereof;

FIG. 6 is a bottom end view thereof; and,

FIG. 7 is a rear view thereof.

The broken lines in the drawings depict portions of the control for heated wearables that form no part of the claimed design.
